Primary Examiner—Wallace R. Burke*Assistant Examiner*—Marcus Jackson*Attorney, Agent, or Firm*—Douglas L. Tschida[57] **CLAIM**

The ornamental design for a blank for changeable alpha numeric characters, as shown and described.

DESCRIPTION

FIG. 1 is a front perspective view of a blank for changeable alpha numeric characters showing my new design with the broken line showing for illustrative purposes only and forming no part of the claimed design;

FIG. 2 is a rear plan view thereof;

FIG. 3 is a top plan view thereof;

FIG. 4 is a bottom plan view thereof; and

FIG. 5 is an enlarged partial front bottom left corner thereof.

FIG. 2

FIG. 3

FIG. 4

FIG. 5
